UNITED STATES PATENT OFFICE.

HENRY W. O'DOWD, OF JERSEY CITY, NEW JERSEY, ASSIGNEE, BY MESNE ASSIGNMENTS, TO STANDARD GAS EQUIPMENT CORPORATION, OF BALTIMORE, MARYLAND, A CORPORATION OF MARYLAND.

BURNER UNIT FOR GAS HEATING APPARATUS.

Application filed, April 24, 1924. Serial No. 708,647.

This invention is directed to an improved burner unit for gas stoves or ranges and for gas heating apparatus in general. The improved burner unit comprises specifically a 5 Bunsen burner member formed with flame ports and a coverplate sustained by said burner member in spaced relation thereto and formed with nozzle openings through which the flame jets project, the coverplate 10 forming in connection with the burner member an interior chamber into which the secondary air is induced and from which it is entrained in proper regulated quantities directly by the flame jets. As the burner unit 15 is thus constructed, the secondary air is supplied and distributed in ample quantity to all of the flame jets in order to insure complete combustion under all conditions of use and without regard to the form or location 20 of the burner member or the disposition of its gas orifices. In actual practice, the improved burner unit has been found to be remarkably efficient and free from many of the objections which characterize prior constructions, the coverplate not only providing for 25 the proper aeration of the burner flames, but serving in addition to prevent contamination of the secondary air supply by the waste products as well as to guard against back 30 pressure, flame deflection, air currents and other influences which interfere with proper combustion or impair the heating efficiency of the burner. The exact construction of 35 the parts and their advantages will best be understood from the detailed description to follow.

In the accompanying drawings:

Fig. 1 is a plan view, partly broken away, of one form of the improved burner unit; 40 Figs. 2, 3 and 4 are sections taken on the lines 2-2, 3-3 and 4-4 of Fig. 1, respectively; .

Figs. 5 and 6 illustrate a modification, Fig. 5 being a cross-section of a portion of 45 the burner shown in the preceding figures, and Fig. 6 a sectional plan view taken on the line 6-6 of Fig. 5;

Fig. 7 is a sectional elevation of a second form of burner unit; 50 Fig. 8 is a plan view thereof; Fig. 9 is a plan view of a third form of burner unit;

Fig. 10 is a section taken on the line 10-10 of Fig. 9;

Fig. 11 is a front view of a range equipped 55 with the improved burner units; and

Fig. 12 is a vertical section taken on the line 12-12 of Fig. 11.

Referring first to Figs. 1 to 4, the Bunsen burner member A therein shown, of a well known type, is formed with two concentric rows of nibs A¹ having orifices through which the gaseous mixture issues and which constitute the flame ports of the burner. Extending across and slightly beyond the 60 burner member is a mixing tube A² provided, as usual, with an air chamber A³ into which the gas is discharged from a nozzle A⁴ under the control of a stop cock or valve A⁵. As shown in Figs. 1 and 4, the central web 70 portion of the burner member is formed with openings A⁶ to allow air (secondary air) to flow upwardly therethrough.

In accordance with the present invention, the Bunsen burner member A is partially 75 enclosed within a coverplate B, which, in this instance, is formed with a depending flange or hood B¹ extending around the outer edge or periphery of the burner member. In its lower edge the flange or hood B¹ is formed with recesses or notches B² engaged with supporting lugs A⁷ cast or otherwise secured to the outer edge of the burner at symmetrically located points. The coverplate is held in place upon the supporting 80 lugs by means of a cotter pin A⁸ passed through a perforated ear piece extended upwardly from the burner member through a centrally located slot B³ in the coverplate. As will be noted, the arrangement of the 85 parts is such that the coverplate B is maintained in spaced relation to the burner member A so as to provide in connection therewith a secondary air chamber C having as its inlet the peripheral opening C¹ created 90 around the lower edge of the flange B¹, as well as the more centrally located openings A⁶ of the burner member. As an outlet for the secondary air chamber C, the coverplate 95 B is formed with discharge nozzles B⁴ arranged directly above the gas nibs A¹ and having their tapered bores or openings disposed in centered relation to the flame ports. In the construction shown, the upper ends of 100

the gas nibs are flush with the under face of the coverplate, but they might be made longer or shorter, if desired. The main consideration is that, when the burner is in use, the 5 flame jets should project through the secondary air discharge openings so as to entrain from the chamber C whatever quantity of secondary air is required to support combustion. In the particular form under discussion, the coverplate is provided with 10 standing posts A¹⁰ which are intended to be used as a support for a cooking utensil.

Many advantages characterize the foregoing construction: For instance, the secondary air is supplied to the burner in substantially pure atmospheric condition and without contamination by the waste products, being drawn into the interior chamber C through the openings C¹ and A⁶ 15 which are located below the level of the flame ports, and then entrained from the chamber directly by the flame jets as they project through the discharge nozzles B⁴. As a matter of fact, the coverplate serves 20 to prevent the secondary air from commingling with the flame jets except through the discharge nozzles. Again, the burner, being protected against the heat of the products of combustion, has less tendency to 25 cause an excessive expansion of the contained gas such as would reduce the entrainment of the primary air. On the other hand, the air pocketed within the coverplate becomes heated by the products of 30 combustion and may therefore be more effectively entrained at the flame ports. In this connection, it may be stated that the tapered bores of the discharge nozzles not only facilitate the proper entrainment of 35 secondary air, but also serve to effect a thorough admixture of the gas and air in promoting combustion. It is also pointed out that, due to the restricted openings of 40 the discharge nozzles, the pressure of the products of combustion at the flame ports is reduced to a minimum, thereby lessening 45 the tendency to back pressure and hence more nearly preserving the initial entrainment of primary air. Moreover, the coverplate 50 protects the burner member from contrary air currents or flame deflection or other moving bodies which might otherwise interfere with proper combustion. These 55 and other advantages will be readily appreciated by those skilled in the art.

The construction shown in Figs. 5 and 6 is substantially the same as above described, except that the flange or hood B¹ of the coverplate is extended down to the level of 60 the under side of the burner member, thus practically completing the enclosure of said member. In this instance, also, the flange, instead of being notched or recessed, as before, is formed with lips B⁵ engaged with 65 recessed supporting lugs A¹¹ on the burner

member, the supporting lugs also serving by their engagement with the inner face of the flange to maintain the coverplate in proper spaced relation to the burner member. 70

In Figs. 7 and 8, the burner member is in the form of a hollow circular box D provided with a single row of nibs D¹ and removably mounted upon a mixing tube D² which communicates therewith through its 75 under side. In other respects the construction is substantially the same as that described in connection with Figs. 1 to 4, the only other notable difference being that the inlet for the secondary air chamber 80 C is limited to the opening C¹ extended around the lower edge of the flange.

In Figs. 9 and 10, the burner member is in the form of a hollow ring E formed with four symmetrically disposed gas nibs 85 E¹ and having an integral mixing tube E² and a central air opening E³. Otherwise, the construction does not differ materially from that first described.

In all the constructions above described, 90 the coverplate B is shown as separate from the burner member and as detachably secured thereto. This arrangement is preferred for reasons of economy and for the further reason that the coverplate may be 95 readily removed to permit the cleaning, repair or replacement of the individual parts. It should be noted, however, that it would be entirely feasible to make the coverplate integral with the burner member, as by casting, 100 and this is contemplated by the present invention. It should also be noted that it is not absolutely essential that the secondary air chamber be common to all of the discharge nozzles of the coverplate, as in the 105 embodiments illustrated, but that a number of such chambers might be provided to serve the discharge nozzles individually or in groups. The particular burner members illustrated have been selected merely by way 110 of example and as representing forms which have heretofore given trouble as regards the proper aeration of the burner flames, and it will be understood, of course, that the invention is susceptible of adaptation to any 115 suitable form of burner member, it being evident that the coverplate may be readily altered in shape or contour to conform to whatever burner member may be employed. Similarly, the particular means employed 120 for supporting the coverplate in proper spaced relation on the burner member are only intended as an example of a simple and practicable embodiment, and may be variously modified to suit the conditions. 125

In Figs. 11 and 12, the improved burner member shown in Figs. 1 to 6 is illustrated as embodied in a gas range of the type covered in my prior Letters Patent No. 1,403,814. As shown, the range presents a closed cook- 130

ing top 27 having removable lids 41 and an underlying combustion chamber 33. The improved burner units (three in the present instance) are located within the combustion chamber at the front only, being supported upon a transverse rod or bar 34 which maintains them the proper distance from the cooking top, the stop cocks or valves A⁵ of the respective units being connected to a common 10 gas supply pipe or manifold 66 situated at the front of the range. As in the prior patent, the combustion chamber is provided at the rear with an outlet 44 for the products of combustion, which outlet communicates 15 with a vertically disposed pipe or conduit 43; and at the front, the combustion chamber is provided with a secondary air inlet opening 36 extending approximately the full width thereof and situated at a level below 20 that of the burner units. When the range is in use, therefore, the secondary air, while free to enter the combustion chamber through its inlet 36, is prevented from commingling with the flame jets except through 25 the discharge nozzles B⁴ of the coverplate B, it being noted that the depending flange or hood B¹ of the coverplate extends down to the level of the secondary air inlet 36 and acts to direct said air upwardly into the 30 chamber C formed between the burner member and the cover plate. In this way, the secondary air required to support combustion is induced into and entrained from the chamber C under the positive control of the 35 flame jets, thus insuring the proper speed of combustion or flame propagation and allowing the burners to be located as near the cooking top as may be desired without giving rise to the objections so common in the 40 use of the ordinary gas burners.

While in some respects the present burner unit is like that covered in my prior Letters Patent No. 1,456,823, it embodies several novel features not disclosed in that patent and which are of considerable value. For instance, in the patent, the burner member is completely enclosed within a box or housing which is supported by the range structure and which in turn affords a support for the burner member. In the present construction, the coverplate is supported directly by the burner member and in fact forms a permanent part thereof, the idea being to construct the several parts as a unit to be used under the same conditions as the ordinary gas burner, but without the objections usually attending the use of such burner. In other words, the improved burner unit is capable of universal use and is designed to possess the various advantages before mentioned wherever and however used. Again, in the patented construction no secondary air is allowed to enter the combustion chamber except through the nozzle openings formed in the upper part of the

box or housing. In the present construction, as illustrated in Figs. 11 and 12, the secondary air is free to enter the combustion chamber through its regular inlet, but is prevented from commingling with the flame jets except through the nozzle openings of the coverplate; hence, many of the advantages of the patented arrangement may be realized without requiring any special construction of the combustion chamber or the range body. These and various other distinctions are fully brought out in the appended claims.

The invention is not, of course, confined to the precise constructions shown and described, nor to any other particular construction by which the same may be carried into effect, as many changes may be made in the details without departing from the main principles of the invention and without sacrificing its chief advantages. It should be understood, therefore, that the invention is not limited to any specific form or embodiment except in so far as such limitations are set forth in the claims.

Having thus described my invention, its construction and mode of operation, what I claim and desire to secure by Letters Patent of the United States, is as follows:

1. A burner unit for gas heating apparatus comprising a Bunsen burner member formed with flame ports, a coverplate sustained by said member in spaced relation thereto and formed with secondary air discharge openings through which the flames project, said coverplate forming with the burner a secondary air chamber and having a depending hood extending around the burner member and spaced therefrom so as to provide a secondary air inlet leading upwardly into the chamber formed between the burner and the coverplate.

2. A burner unit for gas heating apparatus comprising an annular Bunsen burner member formed with flame ports and having a central web, a coverplate sustained by said member in spaced relation thereto and formed with secondary air discharge openings through which the flames project, said coverplate forming with the burner a secondary air chamber, and having a depending hood extending around the burner member and spaced therefrom so as to provide a secondary air inlet leading upwardly into the chamber formed between the burner and the coverplate, and a secondary air discharge opening in said central web.

3. A burner unit for gas heating apparatus comprising a Bunsen burner member formed with flame ports, a coverplate formed with secondary air discharge openings through which the flames project, mutually engaging means formed partly on the burner member and partly on the coverplate for supporting the latter in spaced relation to

the coverplate; said coverplate forming with the burner a secondary air chamber and having a depending hood extending around the burner member and spaced therefrom so

10

as to provide a secondary air inlet leading upwardly into the chamber formed between the burner and the coverplate, and means for

detachably securing the coverplate to the burner member to permit its ready removal or replacement.

In testimony whereof, I have affixed my signature hereto.

HENRY W. O'DOWD.
